UNITED STATES PATENT OFFICE.

ELHANAN L. MOODIE, OF NEW YORK, N. Y.

DESIGN FOR A PAPER-WEIGHT OR CIGAR-HOLDER.

SPECIFICATION forming part of Design No. 20,676, dated April 14, 1891.

Application filed March 2, 1891. Serial No. 383,483. Term of patent 7 years.

To all whom it may concern:

Be it known that I, ELHANAN L. MOODIE, a citizen of the United States, residing at the city, county, and State of New York, have invented a new Alto-Relievo Design for a Paper-Weight and Cigar-Holder, of which the following is a full, clear, and exact description.

In the drawing this design is represented by a perspective view.

10 This alto-relievo design is adapted to use as a paper-weight or as a cigar-rest, or both.

The leading feature of this design is a human face having a border of leaves and a tie and a handle or rest projecting from the mouth.

15 The design of the face is represented at *a*,

with the border of leaves *b* and a representation of a tie *c*, with ends or ribbons *d e*, below the chin, and a spear-head *f* over the forehead. The stem *i* of the rest or handle *h* is represented as passing into the projecting mouth of the face.

I claim—

The alto-relievo design for a paper-weight and cigar-holder, substantially as herein described and shown.

Signed by me this 26th day of February, 1891.

ELHANAN L. MOODIE.
